UNITED STATES PATENT OFFICE.

JOHN P. JOHNSTON, OF OAK PARK, ILLINOIS, ASSIGNOR TO HIMSELF AND
EDWARD E. MORRELL, OF SAME PLACE.

GAS APPARATUS.

SPECIFICATION forming part of Letters Patent No. 664,355, dated December 18, 1900.

Application filed May 14, 1900. Serial No. 16,604. (No model.)

To all whom it may concern:

Be it known that I, JOHN P. JOHNSTON, a citizen of the United States, residing at Oak Park, in the county of Cook and State of Illinois, have invented certain new and useful Improvements in Gas Apparatus, of which the following is a specification, reference being had to the accompanying drawings.

My invention relates to apparatus used in the manufacture of water-gas. In gas apparatus of this character it is usual to supply the oil to the carbureter through feeding or spraying devices arranged in a carbureting-chamber, and consequently subjected to the heat thereof, the result being that the oil-feeding apparatus is soon burned out and has to be replaced. This, I have discovered, can be avoided by providing for automatically withdrawing the oil-feeding devices from the carbureting-chamber when they are not in use. This I accomplish as hereinafter described and as illustrated in the accompanying drawings. What I regard as new will be set forth in the claims.

In the accompanying drawings, Figure 1 is a sectional view of the upper part of a generator, a carbureter, and a superheater, illustrating my invention; and Fig. 2 is an enlarged view, being a partial sectional view on line 2 of Fig. 1.

Referring to the drawings, 1 indicates a gas-generator; 2, a carbureter communicating therewith by registering passages 3 4, extending from the generator and carbureter, respectively, and 5 a superheater.

6 indicates the usual checker-brick in the carbureting-chamber.

7 indicates a passage extending upward from the top of the carbureting-chamber, and 8 a tube which rises from the passage 7 and communicates therewith.

9 indicates a stack, which rises from the top of the superheater and communicates with the superheating-chamber.

10 indicates a cap or valve, which is adapted to close the stack 9. The valve 10 is pivoted on a spindle 11, carried by a crank-arm 12, which is carried by a horizontal shaft 13, pivoted in suitable bearings at the top of the stack, the arrangement being such that by

rocking the shaft 13 the valve 10 can be raised or lowered, so as to open or close the stack.

14 indicates a lever, which is connected to the shaft 13 for operating the same.

15 indicates a hand-lever, which is pivoted to a suitable support 16 and is connected by a connecting-rod 17 with the lever 14, so that the operator by grasping the lever 15 can operate the lever 14 and raise or lower the valve 10 to open or close the stack 9. 60

18 indicates the oil-feeding device, which in the construction illustrated is adapted to be supported in the passage 7, as shown in Fig. 1.

19 indicates a tube, which supports the oil-feeder 18 and rises through the open end of the tube 8. The upper end of the tube 19 is secured by a bracket 20 or other suitable device and a flexible chain or cable 21 to the lever 14, the cable passing around pulleys 22, 70 as shown in Fig. 1. By this construction when the lever 14 is in its uppermost position the valve 10 will lie over and close the stack 9 and at the same time the oil-feeder 18 will be in its lowermost or operative position. 75

When the operator moves the lever 15 down to raise the valve 10 and open the stack, the same operation will raise the oil-feeder 18, drawing it out of the carbureting-chamber and removing it largely from the heat thereof. 80

It will thus be seen that the oil-feeder is subjected to the intense heat of the carbureter only when it is in use, and consequently its life is greatly prolonged. In order to supply oil to the feeder 18 regardless of its position, 85 jointed pipes 23 24 are provided, which communicate with an oil-supply pipe 25 and with the upper end of the tube 19, an angle-valve 26 being provided at the upper end of the tube 19 to permit of the movement of the 90 pipe 23.

Under certain circumstances, such as the breaking down of the automatic mechanism, it may be desirable to raise the oil-feeder by hand, and for this purpose a lever 27 is provided, which is pivoted at one end upon a swinging link 28, suitably supported at the top of the carbureter, said lever being connected to the upper end of the tube 19 by a pivot 29, as shown in Fig. 1. 95 100

While the oil-feeding apparatus is illustrated as being movable in a vertical plane into and out of the carbureting-chamber, it may be arranged in other positions and used 5 for analogous purposes without materially changing the arrangement of the automatic devices for controlling its position. My invention therefore includes such alterations and modifications as would occur to those 10 familiar with the art and is not limited to the specific devices or arrangement illustrated and described, except in so far as such features are specifically claimed.

That which I claim as my invention, and 15 desire to secure by Letters Patent, is—

1. In a gas apparatus, the combination of a heating-chamber, a stack therefor, a valve for said stack, a gas-chamber, a feeding device adjustable in said gas-chamber, and 20 means operated by the movement of the stack-valve for adjusting the position of said feeding device, substantially as described.

2. In a gas apparatus, the combination of a heating-chamber, a stack therefor, a valve 25 for said stack, a gas-chamber, a feeding device movable into and out of said gas-chamber, and means operated by the movement of the stack-valve for moving said feeding de-

vice into and out of said gas-chamber, substantially as described.

3. In a gas apparatus, the combination of a gas-chamber, a feeding device movable into and out of said chamber, a superheater, a stack therefor, a valve for said stack, a lever for operating said valve, and a connecting device 30 connecting said lever and feeding device and so adjusted that when the valve is operated to open the stack the feeding device is automatically moved out of the gas-chamber, substantially as described.

4. In a gas apparatus, the combination of a gas-chamber, a feeding device movable into and out of said chamber, a superheater, a stack therefor, a valve for said stack, a lever for operating said valve, a connecting device 35 connecting said lever and feeding device and so adjusted that when the valve is operated to open the stack the feeding device is automatically moved out of the gas-chamber, and a hand-lever for moving said feeding device 40 out of said gas-chamber, substantially as described.

JOHN P. JOHNSTON.
